UNITED STATES PATENT OFFICE.

PETER S. DUNN, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,290,130.

Specification of Letters Patent.

Patented Jan. 7, 1919.

Application filed April 6, 1917. Serial No. 160,283.

To all whom it may concern:

Be it known that I, PETER S. DUNN, of New Haven, New Haven county, State of Connecticut, have invented certain new and 5 useful Improvements in Locks, of which the following is a full, clear, and exact description.

This invention relates to locks, and more particularly to corridor door locks of hotels and similar buildings, although the invention is applicable to locks of other types.

For the guest rooms of hotels and, in fact, in numerous other buildings, a lock is required which can be opened in case of 15 emergency by a so-called emergency key which is usually kept in the possession of the proprietor or manager. Furthermore, in addition to the ordinary change keys and other keys of low order, the locks of a hotel 20 may usually be operated by what is known as a display key which acts as a shut-out key and locks the door so that it cannot be opened by the guest key, or other keys of low order, although it can be opened by the 25 emergency key.

In the past it has been customary for the emergency key and the display key to act on the same group of tumblers operative by the change key, and consequently the lock 30 construction and more particularly the tumbler mechanism has been made quite complicated and, on the other hand, not particularly secure.

The object of the present invention is to 35 provide a lock construction for doors in which the emergency key and the display key operate the same pin tumbler mechanism but wherein this pin tumbler mechanism is entirely separate and independent 40 from that operated by the change key whereby the security of the latter tumbler mechanism need not be impaired.

Another object of the invention is to provide a lock in which a cylinder mounted on 45 or in the door jamb may be actuated by different keys to operate an emergency mechanism for releasing the door and also a shut-out mechanism for locking the bolt in the strike.

60 The invention also has in view the general improvement in construction and operation of locks of the class to which the invention relates.

To these and other ends the invention

consists in the novel features and combinations of parts to be hereinafter described and claimed.

In the accompanying drawings,

Figure 1 is a fragmentary outside elevation of a door and door frame equipped 60 with a lock construction embodying the invention.

Fig. 2 is an elevation of the door frame or casing showing the jamb and strike.

Fig. 3 is a vertical transverse section 65 through the door frame showing the swinging part of the strike in the locked position.

Fig. 4 is a fragmentary view, similar to Fig. 3, showing the bolt of the lock on the door locked in the strike by actuation of 70 the display key.

Fig. 5 is a view similar to Fig. 3 showing the hinged part of the strike in the open position.

Fig. 6 is a section on line 6—6 of Fig. 4. 75

Fig. 7 is a section on line 7—7 of Fig. 3, showing the emergency key inserted into the cylinder.

Fig. 8 is a view similar to Fig. 7 showing the display key inserted into the cylinder. 80

In the particular example selected for illustration the door is provided with an ordinary mortise lock having a latchbolt and a deadbolt, the deadbolt being operative by suitable key mechanism and the latchbolt 85 being operative by the customary knob mechanism. The casing or frame of the door is provided with a strike plate having openings for the deadbolt and latchbolt, respectively, and a hinged part co-operating 90 with said openings so that when said hinged part is locked in one position it will hold the bolts in the strike, whereas if it is moved to another position it will release the bolts. This hinged part of the strike is controlled 95 by a lock or detent actuated from a cylinder lock on the door jamb into which a so-called emergency key can be inserted for releasing the movable strike member. It will thus be apparent that when the door is 100 locked the possessor of the emergency key may open it by actuating the cylinder lock on the door frame to release the lock for the hinged part of the strike, which can be pushed or pulled to the open position by pushing or pulling on the door. All of

105 these features are not essential parts of my invention in all of its aspects, but they

are mentioned to facilitate understanding of the following detailed description.

- Referring to the drawings,
 A denotes the door,
 5 B the door frame or casing,
 C the lock on the door.
 D the strike on the casing.
 E the auxiliary cylinder lock mounted on
 or in the door jamb, and
 10 F the hinged part of the strike controlled
 from the lock E.

The lock C on the door may be an ordinary mortise lock having a deadbolt 20 and a latchbolt 21, indicated in dotted lines on 15 Fig. 1. The strike D has an opening 22 to receive the deadbolt and an opening 23 to receive the latchbolt. The latchbolt 21 is adapted to be retracted by the knob mechanism G, and the deadbolt 20 is adapted to be 20 actuated by a cylinder lock mechanism H at the outside of the door, having the usual change key.

The strike D is mortised in the door jamb in the usual manner. Its movable part F is 25 hinged at the bottom to the main part of the strike by a pin 24 so that the part F can swing in a vertical plane generally perpendicular to the plane of the door frame. At the lower portion of the hinged member the 30 same is provided with a latch-bolt lip 25, which, when the parts are in the position shown in Fig. 2, closes the latchbolt opening 23 at the inside of the door. At its upper portion the member F is provided with a flange 26 which is adapted to close the deadbolt opening 22 when the member F is in the 35 locked position. Near its upper end the inner face of the member F is provided with a perforated lug or eye 27 by means of which the upper end of member F can be locked 40 to the main part of the strike so as to retain the bolts in the openings 22 and 23. Coöoperating with the lug 27 is a lever 28 pivoted intermediate its ends at 29 between 45 one wall of the strike proper and a cheek 30 adjacent to the upper part of the strike. The lever 28 is adapted to swing in a plane generally perpendicular to that of the door frame and at one end it 50 has a finger 31 adapted to engage the perforated lug 27, while at the opposite end it is adapted to be engaged by suitable cam mechanism on the rear end of the cylinder lock E. The upper end of the main part of the strike 55 is laterally enlarged to provide a portion 32 extending across the jamb in a mortise in the latter, and it is in this part 32 of the strike that the cylinder E is secured by means of a fastening screw 33 extending into a hole in 60 the side of the cylinder. As will be observed from the dotted lines in Fig. 4, the head of the screw 33 is covered by the upper part of the hinged member F when the latter is locked in place by the lever 28 and in order 65 to get at the screw 33 it is first necessary

to release the member F with the emergency key, as hereinafter described.

Pivoted on the main part of the strike, below the lever 28, is a lever 34. This lever is generally similar to the lever 28 and is pivoted intermediate of its ends on a pin 35 extending between the cheek member 30 and the main part of the strike. Obviously both of the levers 28 and 34, are located at the rear face of the strike, in a suitable mortise in the door frame, as shown in Fig. 3. One end of lever 34 is provided with a finger 36 adapted to extend into an opening, or socket, 37, in the upper part of the deadbolt 20, as shown in Fig. 4, while the other end of lever 34 extends into coöperative relation with the cam mechanism of the cylinder E.

Referring to the details of the cylinder lock mechanism E it will be observed that the cylinder lock has the usual casing 38 with a key plug 39 therein, and sectional pin tumblers 40. Surrounding the key plug at the rear thereof is a short sleeve 41 controlled by the rearmost pin tumbler 40^a. In Fig. 8, I have shown a key 42 inserted into the cylinder, which key is termed the display key. This key racks the pin tumblers so that the key plug is released from the casing and from the sleeve, whereas the sleeve is locked to the casing. The key is not sufficiently long to reach and shift the pin tumbler 40^a and therefore the sleeve remains in its normal condition, viz., it is locked to the casing and when the key is inserted the key plug 40 can be rotated individually thereby actuating a cam 43 secured to the rear end of the key plug by screws 44 and co-acting with the inner end of the shut-out lever 34 which locks the bolt in the strike. The short sleeve 41, previously mentioned, carries a cam 45 which is not actuated by the display key 42 owing to the fact that this key does not turn the sleeve. The emergency key 46 will, however, rotate both of the cams 43, 45. This key is longer than the key 42, as shown in Fig. 7, and it is bitted to shift the rearmost pin tumbler 40^a into such a position that the short sleeve is locked to the key plug, but, on the other hand, released from the casing. Therefore, when the emergency key is used, the key plug and sleeve are turned together carrying with them their rollbacks 43, 45, respectively. The rollback, or cam, 45, is designed to actuate the lever 28 controlling the movable part of the strike. For this purpose the cam 45 is provided with talons 47 between which the rear extremity of the lever 28 is adapted to be received. The cam 43 has a cam arm 43^a, by means of which the shut-out lever 34 is engaged and operated, as hereinafter described.

The operation of the improved lock is substantially as follows: The normal position of the parts when the door is open is shown in

Fig. 3. The strike-locking lever 28 is so weighted that the end having the finger 31 normally hangs down in the lug 27 of the part F and when there is no key inserted in the cylinder lock the cam 45 occupies a corresponding position. The finger 36 of lever 34 normally occupies a position above the upper edge of the opening 22 in the strike, as shown in Fig. 3, in which position said lever 34 is held by the cam arm 43^a, as shown. When the door is closed and locked the bolts take into the strike openings, in the usual manner, and the parts 25, 26, of the member F act like integral parts of the ordinary strike. In case of accident or emergency, access can be had to the room from the outside by the proprietor or manager, regardless of the locked condition of the deadbolt 20, for the cylinder lock E may be actuated by the emergency key to release the movable strike member. To do this, the emergency key is turned in a clockwise direction with respect to Fig. 3, thereby carrying downward the inner end of lever 28 and raising the finger 31 out of the lug 27. When the door is then pulled or pushed, the pressure on the bolt 20 will pull or push the hinged part of the strike to the open position in an obvious manner, permitting the door to be fully opened. A partly open position of the member F is shown in Fig. 5.

In using the key 42 as a display key, it is merely necessary to insert it into the lock E and give it a complete rotation in a counter-clockwise direction with reference to Fig. 4. The cam 43 sweeps around loosely, throughout almost a complete rotation, until it almost reaches the position shown in Fig. 4, whereupon the upper edge of the cam arm engages the rear end of lever 34 and pushes the finger 36 down into the opening 37 in the deadbolt. The display key can be taken out of the cylinder lock when the cam 43 is in the locking position shown in Fig. 4. The deadbolt 40 can therefore be left in a locked condition and it will be impossible to release it by the ordinary change key acting on the cylinder lock mechanism H on the door. When it is desired to release the bolt 20, the display key is again inserted and the cam 43 is rotated in the reverse direction, as will be obvious.

It will be apparent that by my invention I provide an extremely simple and inexpensive cylinder lock construction for controlling both the emergency member of the strike and the shut-out mechanism associated with the strike independently of the change key for the lock on the door.

Various changes may be made in the details of the construction without departing from the scope of the invention as defined in the claims.

It will be understood that when the bolt has been locked in the strike by the display

key, as previously described, it will be released when the emergency key is used for opening the strike. If the bolt locking lever 34 is in the operative position and the emergency key is inserted into the cylinder 70 for releasing the hinged part of the strike, the rear end of lever 34 will be lowered by its own weight as the cam 43 is turned to move the cam arm 43^a downward.

What I claim is,

1. The combination with a door and door frame, of a bolt on the door for locking the latter to the frame, a strike on the frame to receive said bolt, and tumbler controlled means associated with said strike and located wholly on the frame, and operable from the outside of the door for locking said bolt in said strike. 75

2. The combination with a door and door frame, of a bolt on the door for locking the latter to the frame, a strike on the frame to receive said bolt, and tumbler controlled means associated with said strike and operable by a key from the outside of the door for locking said bolt in said strike by engagement with the bolt head. 85

3. The combination with a door and door frame, of a bolt on the door, a strike on the frame to receive said bolt, and means including a cylinder lock mortised in the door 95 jamb at the outside of the door, and a pivoted lever operated by the lock for locking said bolt in said strike by engagement with the bolt head. 90

4. The combination with a door and door frame, of a bolt on the door, a strike plate on the frame for receiving said bolt, having a fixed part and a movable part, a member on the frame for locking and releasing the movable part of the strike plate, and a cylinder lock on the frame having a cam to operate said locking and releasing member. 100

5. In a lock construction for doors, a door, a door frame, a lock on the door having a bolt, a strike plate on the frame to receive 110 said bolt, having a fixed part and a movable part, means associated with the frame for locking and releasing said movable part of the strike, means associated with the frame for locking the bolt in the strike, and key actuated mechanism on the frame for operating both of said last named means. 115

6. In a lock construction for doors, a door, a door frame, a lock on the door having a bolt, a strike plate on the frame to receive 120 said bolt, having a fixed part and a movable part, means associated with the frame for locking and releasing said movable part of the strike, means associated with the frame for locking the bolt in the strike, and key actuated mechanism on the frame for operating both of said last named means, said key actuated mechanism including a cylinder lock fitted in an opening of the door jamb. 125

7. In a door lock construction, a door, a door frame, a bolt on the door, a strike plate on the frame having a fixed part and a movable part, a member on the frame to lock and release said movable part of the strike, another member on the frame to dog said bolt in its protracted position in the strike plate, and a single key mechanism mounted in the door jamb for operating both of said members.
8. In a door lock construction, a door, a door frame, a bolt on the door, a strike plate on the frame having a fixed part and a movable part, a member on the frame to lock and release said movable part of the strike, another member on the frame to dog said bolt in its protracted position in the strike plate, and a single key mechanism mounted in the door jamb for operating both of said members, said key mechanism including a cylinder lock whose axis is in a plane substantially parallel to the plane of the door when the latter is closed.
9. An attachment for locks, comprising a strike having a fixed member and a movable member pivotally secured to the fixed member, and cylinder lock mechanism mounted on the fixed member for locking and releasing the movable member.
10. An attachment for locks, comprising a strike having a fixed member and a movable member, a bolt dogging device mounted on the fixed member, and a device mounted on said fixed member for locking and releasing the movable member and the bolt-dogging device.
11. The combination of a strike plate, a shut-cut device mounted thereon for dogging the bolt in the protracted position, and a key actuated mechanism for operating said shut-out device, including a cylinder lock connected with said strike plate.
12. The combination of a strike plate having a fixed part and a movable part, a member on the strike plate for controlling said movable part, another member on the strike plate for dogging the bolt in protracted position, and a cylinder lock on the strike plate having means for operating said members independently by different keys.
13. The combination with a door and door frame of a bolt on the door, a shut-out device on the frame for engaging the bolt head and locking it to the frame, an emergency release device on the frame, and key mechanism for releasing both of said devices simultaneously.
14. An attachment for locks, comprising a strike, a bolt dogging member pivotally mounted upon said strike, and tumbler
- mechanism on said strike for controlling said bolt dogging member.
15. An attachment for locks, comprising a strike having a fixed member and a movable member, a device on said fixed member for locking and releasing the movable member, another device on said fixed member for dogging a bolt by engagement with the head thereof, and tumbler controlled mechanism on said fixed member for controlling both of said devices.
16. The combination with a door and door frame, of a lock on the door having a bolt, a strike on the door frame to receive said bolt, having a fixed part and a movable part, means on the fixed part of said strike for locking and releasing the movable part, means on said fixed part for dogging the lock bolt, and tumbler controlled, key actuated mechanism mortised in the door frame and accessible from the outside of the door for controlling the movable part of the strike and said dogging means.
17. An attachment for locks, comprising a strike having a fixed member and a movable member, said movable member having one end pivotally secured to the fixed member adjacent one end thereof, means at the other end of said fixed member for locking said movable member in its operative position, and a key controlled lock mounted upon said strike adjacent said last mentioned end for operating said locking means.
18. An attachment for locks comprising a strike having a fixed member, a movable member pivotally secured thereto, and a cylinder lock mounted upon the fixed member for locking and releasing the movable member.
19. An attachment for locks, comprising a strike having bolt-receiving notches formed therein, a member pivotally mounted on said strike adjacent one end thereof for closing the opened side of said notches, means upon the opposite end of said strike for locking said pivoted member in its operative position, and a key controlled lock mounted upon said strike adjacent said last mentioned end for operating said locking means.
20. An attachment for locks comprising a strike plate having a notch formed therein for receiving the end of a protracted bolt, a member movably mounted upon said strike plate for closing the opened side of said notch, and a cylinder lock for locking said movable member in its notch-closing position.

In witness whereof I have hereunto set my hand this 4th day of April, 1917.

PETER S. DUNN.
